UNITED STATES PATENT OFFICE.

FERDINAND GROTE, OF EVANSVILLE, INDIANA.

FORCE-PUMP.

SPECIFICATION forming part of Letters Patent No. 291,845, dated January 8, 1884.

Application filed September 24, 1883. (No model.)

To all whom it may concern:

Be it known that I, FERDINAND GROTE, a citizen of the United States, residing at Evansville, in the county of Vanderburg and State 5 of Indiana, have invented certain new and useful Improvements in Double-Acting Force-Pumps, of which the following is a specification, reference being had therein to the accompanying drawings.

10 My invention has relation to double-acting force-pumps; and the object of the invention is to produce a pump for the rapid and efficient raising and forcing of water, that will be simple and cheap in construction and adapted to the various wants of the general public, for 15 household, farm, and fire uses; and to these ends the novelty consists in the construction of the same, as will be hereinafter more fully described, and particularly pointed out in the 20 claims.

In the accompanying drawings similar letters of reference indicate like parts of the invention.

Figure 1 is a sectional elevation of my 25 proved pump set up for operation, and Fig. 2 an elevation of the pumping-cylinders.

A is the standard, and its upper end is provided with a casting, B, which forms the air-chamber delivery-spout and support for the 30 handle C. To the lower end of this standard A is secured a hollow connection, D, the lower end of which is tapped to receive the brace E, rigidly secured thereto by the lock-nut e, and the lower end of said brace is screwed into 35 the casting F, which is provided with lateral branches a a and inlet a', into which is screwed the suction-pipe G, the lower end of which enters the well or water-supply.

To the branches a a of the casting F are secured the elbows H H by means of the bolts h passing through the ears h' on said elbows, so as to securely clamp the casting F between them, the joints between said casting and elbows being packed with rubber or leather 45 washers in the usual manner.

I I are the foot-valves, and are of the usual construction.

K K are the lower and L L the upper cylinders.

M M are the piston-rods, and each one is 50 provided with a small piston, m, working in the upper cylinder, L, and a large piston, n, provided with a valve, n', working in the lower cylinder, K, said piston-rods and pistons being of the usual construction.

N is a boss cast upon the side of the cylinders L L, and is provided with ears O O on the outside, and an opening, P, which forms the outlet for both the upper and lower pairs of cylinders. The rods p pass through the ears 60 O O on the bosses N, and by means of the nut s securely clamp the cylinders L L together with the connection D between them, the joints being packed in the ordinary way with a washer.

t t are ears cast upon the lower end of the cylinders K K, and similar lugs, k k, are on the elbows H H, and through the ears t and k passes a rod, V, having nuts v v, so that the elbow and cylinder may be rigidly secured 70 together.

The pump operates in the usual manner, and further description is deemed unnecessary.

What I claim, and desire to secure by Letters Patent of the United States, is—

1. The combination, with the cylinders L L, having bosses N N, and ears o o, of the connection D and rods p, as and for the purpose set forth.

2. The combination, with the standard A, connection D, and cylinders L L and K K, of the screw-threaded rod E, elbows H, and casting F, substantially as set forth.

3. The combination, with the cylinders K K, having lugs t t, of the elbows H H, having lugs k k and k' k', and the casting F and bolts V and h, and their nuts, as and for the purpose set forth.

In testimony whereof I affix my signature in 90 presence of two witnesses.

FERDINAND GROTE.
